(57) **CLAIM**

The ornamental design for an electronic musical instrument with keyboard, as shown and described.

DESCRIPTION

FIG. 1 is a perspective view of an electronic musical instrument with keyboard showing my new design;

FIG. 2 is a top plan view thereof;

FIG. 3 is a front elevation view thereof;

FIG. 4 is a rear elevation view thereof;

FIG. 5 is a bottom plan view thereof;

FIG. 6 is a left side elevational view thereof; and,

FIG. 7 is a right side elevational view thereof.

The portions of an electronic musical instrument with keyboard in broken lines are shown for illustrative purposes only and form no part of the claimed design.
